UNITED STATES PATENT OFFICE.

WALTER L. JONES, OF WEST SOMERVILLE, MASSACHUSETTS, ASSIGNOR TO LEVER BROTHERS COMPANY, OF CAMBRIDGE, MASSACHUSETTS, A CORPORATION OF MAINE.

SOAP-CUTTING MACHINE.

Application filed November 15, 1924. Serial No. 750,038.

The invention relates to an improvement in soap cutting machines.

In the production of milled soap, the soap is delivered as a continuous stream from the plodder. It is common practice at the present time for the operative to cut off from this stream of soap a bar of predetermined length which he places in front of the constantly reciprocating plunger by which the soap is pressed through the cutting devices of the soap cutting machine which cut up the length of soap into relatively short bars or cakes for hand and laundry use. The object of the present invention is to provide a soap cutting machine of this type with a mechanism which will operate automatically to perform the same operations (but in a more efficient manner) now performed by the operative in cutting off the requisite length of soap from the stream issuing from the plodder and placing it in front of the plunger. To this end the invention consists in the improved soap cutting machine hereinafter described and particularly pointed out in the appended claims.

In the accompanying drawings illustrating the preferred form of the invention, Fig. 1 is a plan of the improved soap cutting machine, and of the nozzle of the plodder; Fig. 2 is a longitudinal section taken along the line 2—2 of Fig. 1, looking in the direction of the arrows; Fig. 3 is a section, on an enlarged scale, taken along the line 3—3 of Fig. 2; Fig. 4 is a side elevation of the machine shown in Fig. 3, looking from the right; Fig. 5 is a perspective view, on an enlarged scale, of the trip mechanism and associated parts; Fig. 6 is a detail in plan of the movable knife (and associated parts) for cutting off bars of predetermined length from the stream of soap issuing from the plodder; and Fig. 7 is a section taken along the line 7—7 of Fig. 6.

The mechanism of the present invention may be applied to and used in connection with any usual or preferred form of soap cutting machine. The milled soap to be cut up into small bars or cakes of the requisite size and shape issues as a continuous stream 10 from the nozzle 11 of the plodder 12, the construction and operation of which is familiar to those skilled in the art. The mechanism of the present invention operates to cut off a predetermined length 14 from the continuous stream of soap issuing

from the plodder and to deliver it in front of the constantly and regularly reciprocating plunger 15 by which it is forced through the cutting devices which cut it up into relatively small cakes.

The plunger 15 extends throughout the length of the machine and reciprocates on a table 16 supported by the frame work 17 of the machine, the lower portions of which resting on the floor are not shown in the drawings. The plunger 15 is actuated from the motor 18, the connections between the motor and the plunger consisting of a worm 19 mounted on the outer end of the motor shaft 20 and driving a worm gear 21 housed in the casing 22. On one end of the shaft 24 of the worm gear 21 is a pinion 25 which meshes with and drives a gear 26 (Fig. 4) mounted on a longitudinally arranged shaft 27 which is journaled in the frame work of the machine. On each outer end of the shaft 27 is mounted a crank disc 28 connected by means of the connecting rod 29 with the lower end of the rocker arm 30. The upper free end of each rocker arm is pivotally connected by means of the link 31 with a rod 32 which is loosely received in the slot 33 which extends throughout the length of the plunger 15. The purpose of this lost motion between the rod 32 and the plunger 15 will appear as the description proceeds.

The relatively long bars or lengths of soap 14 which are cut off from the stream of soap issuing from the plodder by the mechanism of the present invention and delivered to a position in front of the plunger 15, are forced by the plunger through cutting devices consisting of a series of wires 35 and cutters 36 secured in a frame work generally indicated at 37 by which the long bars of soap are cut into short bars or cakes of the desired size and shape. The frame work 37 carrying the soap cutters is positioned beyond the limit of the forward movement of the plunger 15 a distance equal to the thickness of two or three bars of soap. This arrangement is a convenient one for permitting the operative to avoid improper cutting or other accidents before the plunger forces a bar through the cutters. By this arrangement it will be understood that only the length of soap immediately in front of the cutters will be forced through them by the forward movement of the plunger, and that before this operation can take place two

- or three other lengths of soap must be interposed between the plunger and the length of soap next to the cutters. The small bars or cakes emerging through the cutters are delivered onto a platform 38 from which they are removed by the operative. In their general features the parts described above are constructed and operate as usual in soap cutting machines.
- 10 The mechanism of the present invention comprises a movable cutter or knife 40 for cutting the predetermined length of soap from the soap stream 10 and a reciprocating feed bar 41 which functions to cooperate with the knife 40 to cut off the predetermined length of soap and also to deposit it in front of the plunger 15. The feed bar 41 is mounted to reciprocate on the upper surface of a longitudinally arranged guard 20 or housing 42 open at its front side and under which the plunger 15 is received at the limit of its rearward movement. The reciprocating movements are imparted to the feed bar 41 from the crank discs 43 pivotally connected with the outer ends of the bar 41 by the connecting rods 39 and 44. The crank discs 43 are mounted on each outer end of a shaft 45 journaled in the bearing blocks 46 rising from the rear edge of the table 16.
- 25 The shaft 45 is driven from a shaft 51 by a chain 48 which passes over a sprocket wheel 49 mounted on the middle of the shaft 45 and over a sprocket wheel 50 mounted on the shaft 51 which is journaled in the upper yoke-like end of the upright 52 which rests on the platform 53 supported by the cross-pieces 54, upon which platform the motor 18 and the casing 21 are supported.
- 30 The shaft 51 is provided on one end with a bevel gear 56 which meshes with and is driven by a bevel gear 57 mounted on one end of a shaft 58 journaled in the upper end of the upright 59 supported by the platform 53. On the other end of the shaft 58 is fixed a large bevel gear 60 which meshes with and is driven by a large bevel gear 62 mounted on one end of the shaft 24. The feed bar 41 is prevented from vertical displacement by guides 64 which loosely engage with the ends of the feed bar. The guides 64 are angle-shaped pieces mounted on the housing 42 and have an open forward side to permit the reciprocation of the feed bar.
- 35 The cutter 40, with which the feed bar 41 cooperates to cut off the predetermined length of soap from the soap stream 10, is a flat vertically arranged knife blade secured to the outer end of a knife bar 65 slidingly mounted in the knife support 66 which is a box-like structure partly supported on the left hand end of the machine and partly supported by the bracket 67 (Fig. 2). In order that there may be no binding of the knife bar during its sliding movements while

the knife 40 is operating to cut the soap and is returning to normal position, the bottom surface of the knife bar is engaged by the roller bearings 68, the forward end of the bar is engaged by the roller 69, and the rear end of the bar carries a roller 70 which engages with a flange 71 rising from one side of the knife support 66. The knife bar is prevented from vertical displacement by the roller 72 mounted on a boss 73 rising from the support 66. This arrangement of the knife bar is for the purpose of permitting the knife to engage with the soap stream issuing from the plodder, travel therewith during the act of cutting off a length of soap, and to return to normal position after the soap has been cut. The means for retracting the soap bar comprises a weight 75 (Fig. 2) connected by the flexible strip 76 with the pin 77 upon which the roller 70 is pivoted. The flexible strip 76 passes over the pulley 78 mounted in the outer ends of the bracket 79 secured to the support 66. A screw 80, which takes against the free end of the knife bar 65, determines the operative position of the knife 40.

As the stream of soap 10 issues from the plodder 12 it passes over the rolls 82 mounted in a bath of oil in a box-like structure 83 resting on the extension 84 of the table 16. The soap stream is guided laterally between the vertically arranged rolls 85 mounted on the extension 84. From the guide rolls 85 the soap stream is directed through the U-shaped guide 86, open at its upper side, mounted to reciprocate laterally in the head portion 87 of the knife bar. For this purpose the wall 88 of the guide 86 is provided with two laterally extending pins 89 (Figs. 6 and 7) which are loosely received in the transverse holes 90 in the head of the knife bar 65. The forward end of the guide 86 closely engages with the rear side of the knife 40 in order that no soap may pack in between the end of the guide 86 as it reciprocates and the rear side of the knife. Moreover, by providing a close engagement between the guide and the knife a more effective cutting action is secured.

When a predetermined length of soap has passed by the cutting edge of the knife, the feed bar 41 is moved forward to carry the guide 86 with it and press the soap stream against the cutting edge of the knife. Inasmuch as the soap stream continues to issue from the plodder during the cutting action, the knife 40 and the parts connected with it, are carried forward with the soap stream. To eliminate friction between the front face of the feed bar 41 and the side 92 of the forwardly traveling guide 86, the left hand end of the front wall of the feed bar 41 is provided with a series of vertically arranged rolls 93 against which the outside of the wall 92 bears as the guide 86 moves forward with

the knife when the latter is engaged by the soap stream. A roller 94 pivoted on a pin extending laterally from the top edge of the wall 92 bears against the adjacent edge 5 of the top surface of the slotted plate 95 secured to the top of the left hand end of the feed bar 41. The plate 95 serves the purpose of returning the guide 86 to its normal position upon the completion of the soap cutting operation. The rollers 96 carried by the upper surface of the wall 88 of the guide 86 project upwardly through the slot in the plate 95 and are engaged by the outer edge 97 of the plate 95. The rollers 96 eliminate friction as the knife bar 65 returns to normal position while the feed bar 41 is retracting the guide 86 by the engagement of the plate 95 with the rollers 96.

The length of soap 14 (Fig. 1) to be cut from the soap stream 10 is determined by the engagement of the end 98 of the soap stream with the wheel 99 of the trip mechanism which controls the means for actuating the feed bar 41. The wheel 99 is carried on the lower free end of an arm 100 mounted on the outer end of a shaft 102 pivoted in the bearings 103 and 104 of the horizontal arm of the bracket 105, the base 106 of which is adjustably secured to the table 16. The lower end of the arm 100 is yieldingly held in the position shown in Figs. 2 and 5 by means of the torsion spring 107, one end of which is fixed in the bearing 103 and the other end of which is connected with the outer end of the shaft 102.

After the end 98 of the soap stream strikes the wheel 99 and operates the trip mechanism to cause the feed bar 41 to be advanced to deposit the soap length 14 in front of the plunger 15, the spring 107 returns the arm 100 and wheel 99 to normal position in the path of travel of the soap stream. The operative position of the wheel 99 may be adjusted by means of the set screw 117 which is threaded in a boss 118 projecting from the horizontal arm of the bracket 105, the free end of the screw 117 bearing against the latch 109 secured to and projecting downwardly from the shaft 102, as shown in Fig. 5.

When the arm 100 and shaft 102 are oscillated by the engagement of the wheel 99 by the end 98 of the soap stream, the latch 109 engages with a dog 110 secured to the rod 111, the right hand end of which passes loosely through a block 112, and the left hand end of which is pivotally connected with the upper arm 113 of a bell crank lever 114 pivoted at 115 on the underside of the table 16. The lower arm 119 of the bell crank 114 is provided at its extremity with a hook 120 adapted to be engaged by a corresponding hook-like part 121 of a clutch mechanism 122. The construction of this clutch mechanism is such that when the hook 120 is disengaged from the part 121 of the clutch, the gear 57 is operately connected with the constantly driven part of the shaft 58 upon which the gear 60 is mounted, thereby driving the gear 56 and the parts 79 connected with it to actuate the feed bar 41. When the hook 120 is held in the path of rotation of the part 121, the gear 57 is disconnected from the active part of the shaft 58 and the parts driven by the gear 57 are brought to a stop. The contraction spring 124, one end of which is connected with the upper end of the arm 113 and the other end of which is connected with a pin 125 rising from the housing 42, serves to yieldingly hold the hook 120 in the path of travel of the part 121 of the clutch mechanism. When the latch 109 engages with the dog 110 to move the rod 111 to the right, the bell crank 114 is turned in a clockwise direction, thereby disengaging the hook 120 from the part 121 to bring about the actuation of the feed bar 41. One rotation of the clutch mechanism causes one complete reciprocation of the feed bar.

The feed bar is actuated to push the soap stream against the knife or cutter 40 only when a predetermined length of soap has passed by the cutter. The spring 124 is provided to return the hook 120 into the path of travel of the part 121 of the clutch to stop the actuation of the feed bar after the latter has moved forward to cause the soap to be cut and deliver the bar just cut to a position to fall in front of the plunger 100 and has returned to normal, retracted position out of the path of travel of the soap stream. When the end of the soap stream engages with the wheel 99 and moves it to the right, the parts connected with the wheel 99 are held in their moved position until the forward movement of the feed bar disengages the cut bar of soap from the wheel 99. In order to disengage the dog 110 from the latch 109, when the latter has been moved to and is held in its right hand position, to permit the spring 124 to move the hook 120 into the path of the part 121 of the clutch to prevent a second forward movement of the feed bar until the proper amount of soap has passed by the cutter, a release mechanism for the dog 110 is provided, consisting of an arm 127 pivoted on the upright 128 (Fig. 5). One end of the arm 127 projects over the upper surface of the connecting rod 44 while the latter is in its position of rest, which is about the middle of its vertical oscillation, as is understood by viewing Fig. 4. The other end of the arm 127 is connected by the wire 129 with the block 112 through which the outer end of the rod 111 loosely passes. The block 112 is mounted to slide vertically in the upper bifurcated end of the bracket 130 rising from the table 16. A spring 132 in-

terposed between the top 133 of the bracket 130 and the head 134 of the screw 135 threaded into the top of the block 112 serves to normally hold the right hand end of the rod 111 raised with the dog 110 in the path of oscillation of the latch 109 and the arm 127 in position to be engaged by the connecting rod 44 when the latter rises during its forward movement caused by the rotation of the crank pin 136 when the shaft 45 is actuated. When the arm 127 is engaged and oscillated by the connecting rod 44 the block 112 is pulled down, thereby freeing the dog 110 from engagement with the latch 109 and permitting the spring 124 to pull the rod 111 and the dog 110 to normal position. When these movements have taken place and the connecting rod has returned to normal position, the spring 132 raises the block 112 and with it the dog 110. The disengagement of the wheel 99 from the end 98 of the soap stream after the feed bar 41 moves forward permits the spring 107 to return the arm 100 and latch 109 to normal position, the latch 109 depressing the dog 110 and the block 112, which are again raised by the spring 132 when the latch 109 passes to position in front of the dog 110.

In case the spring 124 should fail for any reason to return the hook 120 into the path of travel of the part 121 before the latter has made one revolution, the arm 119 of the bell crank 114 is provided with an offset detent arm 138 (Fig. 2) adapted to be engaged by the cam surface 139 of the clutch as the latter rotates. The engagement of the cam surface 139 with the end of the detent arm 138 causes the bell crank 114 to be rotated in a counter-clockwise direction and the hook 120 to be moved into the path of the part 121.

The plunger 15 reciprocates constantly at a regular, determined speed. The rate of reciprocation of the feed bar 41 is determined by the speed of the soap stream issuing from the plodder. This speed, as is well-known to those skilled in the art, varies from about 8 feet to 35 feet per minute, depending upon the amount and consistency of the ground soap contained in the plodder. Hence, the reciprocations of the feed bar and the reciprocations of the plunger will vary irregularly. When the feed bar is actuated to move forward to cooperate with the knife 40 to sever a bar of soap of predetermined length from the soap stream and to push it forward into position to drop in front of the plunger 15, the plunger may be at any point in its forward or rearward movements. If the plunger has already started forward and has advanced far enough beyond the forward edge of the housing 42 so that the freshly severed bar of soap will drop on top of the plunger when the feed bar moves forward, the bar of soap will remain on the

plunger until the plunger has completed its forward movement and has retracted within the housing 42, as shown in Fig. 3, whereupon the bar of soap will fall in front of the plunger. This freshly severed bar of soap which is prevented from immediately falling in front of the plunger when it is pushed forward by the feed bar, because of the position of the plunger, does not interfere with the stream of soap coming from the plodder. This is because the feed bar on its forward movement to sever the soap pushes the severed bars beyond the forward edge of the housing 42 and against a longitudinally arranged guard rail 141 slidably mounted at each end on the pins 142 projecting forwardly from the forward edge of the housing 42. The contractile springs 143 yieldingly hold the guard rail in its normal position spaced from the forward edge of the housing 42 substantially the width of the thickness of the bar of soap and permit the guard rail 141 to yield in case of a jam. The freshly severed bar of soap is held between forward edge of the housing 42 and the guard rail 141 until the plunger 15 has been retracted within the housing. This arrangement and mode of operation removes the severed bar of soap from the path of travel of the soap stream when the rearward movement of the feed bar 41 pulls the guide 86 and new forward end of the soap stream from the position shown in Fig. 6 (which shows the positions of the parts upon the completion of the cutting operation) back to their normal position shown in Fig. 1. The stream of soap issuing from the plodder being flexible readily permits this mode of operation.

It sometimes happens that the plunger 15 emerges from the housing 42 just as the feed bar 41 is completing its forward movement. In such a case (which in practice occurs very seldom), the freshly severed bar of soap would drop far enough in front of the advancing plunger to be caught thereby and pushed against the guard rail 141. To avoid any such eventuality and the jam that might occur if it happened, the plunger 15 is provided with the longitudinal slot 33 to permit relative movement between the plunger and the rod 32, and means operative in such a contingency are provided to connect the plunger with the feed bar 41 to move the plunger forward with the latter sufficiently far to prevent the freshly severed bar of soap from falling in front of the advancing plunger. This mode of operation is possible, because, although the plunger 15 reciprocates regularly and the feed bar reciprocates irregularly, the latter travels at a higher rate of speed than the plunger. When the plunger has been retracted within the housing 42 by the rearward movement of the rod 32 and its engagement with the

rear side of the slot 33, the rod 32 immediately begins its forward movement. The plunger 15, however, remains stationary until the rod 32 contacts with the forward side 5 of the slot 33. If the feed bar is advanced before the rod 32 reaches the forward side of the slot 33, the plunger will be carried forward with the feed bar until the rear side of the slot strikes the rod 32. The 10 freshly severed bar of soap will then fall on the forward end of the plunger, as shown in Fig. 7.

The connections between the plunger and the feed bar, which are operative only under 15 the conditions described, comprise the rearwardly extending fingers 145 having a down-turned end 146 (Fig. 3) loosely received within the slots 147 in the rear part of the upper surface of the housing 42. The down-turned ends 146 of the fingers 145 are arranged to engage with the rearwardly extending pins 148, the heads 149 of which are slidably received in the bored holes 150 in the rear side of the plunger. Each pin 20 is provided with an expansion spring 151 which forces it outwardly into position to be engaged by the downturned end of its finger 145.

It will be understood that it is only necessary for the forward edge of the plunger 15 to project beyond the forward edge of the housing 42 but a short distance in order to catch and hold up the freshly severed bar of soap. If, now, it is considered that the plunger has been retracted within the housing 42 and the rod 32 has not yet reached the forward side of the slot 33 as the feed bar is completing its forward movement, it will be seen that the freshly severed bar of soap 25 will drop down past the forward edge of the housing 42 and in front of the plunger. If the relative positions of the feed bar and the rod 32 are such that the rod 32 strikes the forward side of the slot 33 as the feed bar is completing its forward movement, the engagement of the fingers 145 with the pins 148 will carry the plunger forward synchronously with the relatively fast forward movement of the feed bar, thereby causing 30 the plunger to catch the falling bar of soap on top of its forward end. The plunger will then momentarily remain stationary until the forwardly moving rod 32 again engages with the forward side of the slot 33 and completes the forward movement of the plunger, the plunger sliding under the bar of soap which is held between the guard rail 141 and the forward edge of the housing 35 until the plunger has again been retracted within the housing. If the plunger 15 is retracted within the housing 42 and the rod 32 is in engagement with the rear side of the slot 33 (as shown in Fig. 3), when the feed bar 41 begins its forward movement, the spring 151 will be compressed, thereby per-

mitting the forward movement of the feed bar while the plunger remains stationary.

The mode of operation of the various parts of the improved soap cutting machine has been indicated in connection with the description of their construction. It will be convenient to describe briefly the mode of operation of the machine as a whole: As the soap stream 10 issues from the plodder, it passes through the guide 86 and continues 70 until it strikes the wheel 99 and moves the arm 100 to the right, oscillating the shaft 102 in a counter-clockwise direction. During this forward travel of the soap stream until the forward end 98 thereof reaches 75 and moves the arm 100 to the right, the feed bar 41 remains in retracted, normal position, as shown in Fig. 1. The operation of the trip mechanism by the engagement of the end 80 of the soap stream therewith releases the clutch 122 and causes the feed bar to move forward carrying the guide 86 with it, thereby pressing the soap against the knife cutter and severing it. The forward movement of the feed bar with the guide 86 against the knife causes the soap to be deflected from its normal path of travel, as shown in Fig. 6. The soap, however, continues to advance and carries the knife and guide with it until the rearward movement 85 of the feed bar disengages the guide 86 and the new forward end of the soap stream from the knife. The rearward movement of the feed bar serves to restore the guide 86 and the soap stream to their normal position. When the new forward end of the soap stream has been disengaged from the rear side of the cutter 40, the weight 75 returns the cutter to normal position.

The oscillation of the shaft 102 by the engagement of the forward end of the soap stream with the wheel 99 causes the latch 109 to move the dog 110 and the rod 111 to the right, thereby oscillating the bell crank 114 in a clockwise direction and disengaging the hook 120 from the part 121 of the clutch mechanism, permitting the latter to make one revolution. The forward edge of the feed bar 41, when the latter is at the limit of its forward movement, projects slightly beyond the forward edge of the housing 42 (as indicated in Figs. 6 and 7) so that as the predetermined length of soap is severed from the soap stream, it drops in front of the forward edge of the housing 42 and in front of the plunger 15, if the latter happens to be retracted within the housing, but on top of the plunger if it happens to be on its forward or rearward movement. If the plunger is starting forward just before the feed bar reaches the limit of its forward movement, the plunger will be carried forward synchronously with the feed bar by the engagement of the fingers 145 with the pins 148 and the severed bar of 105 110 115 120 125 130

soap will drop onto the upper surface of the forward edge of the plunger. As shown in Fig. 3 the limit of the forward movement of the plunger 15 is distant from the cutting devices by which the soap bars are cut into cakes of the requisite size and shape a space equal to the thickness of three soap bars. Consequently when a freshly severed soap bar falls in front of the plunger 15 and is carried forward thereby, it does not reach the cutting devices until the third subsequent forward movement of the plunger.

Although the mechanism of the present invention is particularly applicable to soap cutting machines, it will be understood that it is not to be restricted to this purpose, inasmuch as it is equally applicable to other machines in which articles are irregularly fed to a constantly and regularly reciprocating plunger which delivers the articles to the desired position or performs some other operation upon the articles. The mechanism of the invention is shown and described as applied to a soap cutting machine by way of illustration, and its more general adaptability will be readily understood from this specific use.

Having thus described the invention what I claim as new is:—

1. A soap cutting machine having in combination with a plodder which delivers soap in a continuous stream, a constantly reciprocating plunger, cutting devices through which the plunger is adapted to force a bar of soap cut from the soap stream, means for actuating the plunger, a movable knife located beside the path of travel of the soap stream, a feed bar adapted to push the soap stream against the cutter to cut from the soap stream a bar of predetermined length, said bar acting to deliver the bar of soap in front of the plunger, means for actuating the feed bar, and means arranged to be engaged and moved by the soap stream when a predetermined length has been delivered from the plodder for controlling the operation of the means for actuating the feed bar.

2. A soap cutting machine having in combination with a plodder which delivers soap in a continuous stream, a constantly reciprocating plunger, cutting devices through which the plunger is adapted to force a bar of soap cut from the soap stream, means for actuating the plunger, a knife mounted beside the path of travel of the soap stream and arranged to move with the soap stream when engaged thereby, a feed bar for pushing the soap stream against the knife, means for actuating the feed bar, and a trip mechanism for controlling the operation of the feed bar actuating means, said trip mechanism having a part located in the path of travel of the soap stream and arranged to be

moved thereby when a predetermined length of soap has been fed past the cutter.

3. A soap cutting machine having in combination with a plodder which delivers soap in a continuous stream, cutting devices, a plunger for forcing a bar of soap cut from the soap stream through the cutting devices, means for actuating the plunger, a knife located beside the path of travel of the soap stream and arranged to move with the soap stream when engaged thereby, a feed bar for pushing the soap stream against the knife to cut from the soap stream a bar of predetermined length, means for actuating the feed bar including a clutch and a trip mechanism for controlling the clutch, said trip mechanism having a part located in the path of travel of the soap stream and arranged to be moved thereby when a predetermined length of soap has been fed past the cutter to release the clutch to cause the feed bar to push the soap stream against the knife.

4. A soap cutting machine having in combination with a plodder which delivers soap in a continuous stream, a plunger arranged to reciprocate on a plane lower than the plane of the soap stream, cutting devices through which the plunger forces a bar cut from the soap stream, means for actuating the plunger, a knife located beside the path of travel of the soap stream and arranged to move therewith when engaged thereby, a feed bar located on the plane of the soap stream for pushing the soap stream against the cutter to cut therefrom a bar of predetermined length, means for actuating the feed bar, and a trip mechanism for controlling the operation of the feed bar actuating means, said trip mechanism having a movable part located in the path of travel of the soap stream and arranged to be actuated thereby when a predetermined length of soap has been fed past the cutter, said feed bar acting to deliver the bar of soap cut from the soap stream to a position to drop in front of the plunger.

5. A soap cutting machine having in combination a plodder which delivers soap in a continuous stream, a constantly reciprocating plunger located on a plane below the plane of the soap stream, cutting devices through which the plunger is adapted to force a bar of soap cut from the soap stream, means for actuating the plunger, and a mechanism for delivering the bar of soap to a position in front of the plunger comprising a movable knife located beside the path of travel of the soap stream, a feed bar arranged to push the soap stream against the knife, means for actuating the feed bar, the operation of which is controlled by the soap stream, and a trip mechanism actuated by the soap stream when a predetermined length of soap has been fed past the cutter

for controlling the operation of the feed bar actuating means, said feed bar acting to push the bar of soap cut from the soap stream to a position to fall in front of the 5 plunger.

6. A soap cutting machine having in combination with a plodder which delivers soap in a continuous stream of variable speed, a plunger located on a plane below the plane 10 of the soap stream, cutting devices through which the plunger is adapted to force a bar of soap cut from the soap stream, and a mechanism for delivering the bar of soap to a position in front of the plunger comprising 15 a knife, a feed bar for forcing the soap stream against the knife, means for actuating the feed bar, and a trip mechanism for controlling the operation of the feed bar actuating means, said trip mechanism having 20 a part located in the path of travel of the soap stream and arranged to be moved thereby when a predetermined length of soap has been fed past the knife, said feed bar acting to push the bar of soap cut from 25 the soap stream to a position to fall in front of the plunger.

7. A machine for cutting soap having in combination with a plodder for delivering the soap in a continuous stream, cutting devices, a constantly reciprocating plunger for forcing a bar of soap cut from the soap stream through the cutting devices, a knife, means for causing the knife to sever the soap when a predetermined length of soap 30 has passed by the knife, and means for delivering the severed bar of soap to position in front of the plunger.

8. A soap cutting machine having in combination with a plodder for delivering the 40 soap in a continuous stream, a plunger reciprocating at a regular speed, cutting devices through which the plunger forces a bar cut from the soap stream, means for actuating the plunger, a movable knife located beside the path of travel of the soap stream and mounted to move with the soap stream while it is severing a predetermined length from the said stream, means for pushing the soap stream against the knife 45 and for retracting the soap stream from the knife, and a trip mechanism controlling the operation of the means for pushing the soap stream forward, the severed bar of soap being in position to drop in front of the 50 plunger after the latter has been retracted.

9. A soap cutting machine having in combination with a plodder for delivering the soap in a continuous stream, a plunger reciprocating at a regular speed, cutting devices through which the plunger forces a bar of soap cut from the stream, means for actuating the plunger, a reciprocating feed bar, means for actuating the feed bar the operation of which is controlled by the soap 60 stream, a trip mechanism through which the 65

soap stream controls the operation of the means for actuating the feed bar, and a knife against which the feed bar forces the soap stream when a predetermined length of soap has passed by the knife, said feed 70 bar acting to push the severed bar of soap to position from which it will fall in front of the plunger when the latter has been retracted.

10. A soap cutting machine having in 75 combination with a plodder for delivering the soap in a continuous stream, a plunger located on a plane below the soap stream and arranged to reciprocate at a regular speed, means for actuating the plunger, 80 there being lost motion between the plunger and its actuating means so that the plunger pauses at the end of its forward movement and at the end of its rearward movement, cutting devices through which the plunger 85 forces a bar of soap cut from the soap stream, a knife located beside the path of travel of the soap stream, a reciprocating feed bar the movements of which are controlled by the soap stream, means for actuating the feed bar, a trip mechanism having 90 a part in the path of travel of the soap stream and arranged to be moved thereby to control the operation of the means for actuating the feed bar, and yielding connections between the feed bar and the plunger operative when the feed bar is completing its forward movement and the plunger has just begun or about to begin its 95 forward movement for carrying the plunger 100 forward with the feed bar a short distance.

11. A soap cutting machine having in combination with a plodder which delivers the soap in a continuous stream, a plunger reciprocating at a regular speed on a plane 105 below the plane of the soap stream, cutting devices through which the plunger is adapted to force a bar of soap cut from the soap stream, and a mechanism for feeding to the plunger the bars of soap comprising a trip 110 mechanism for determining when a predetermined length of soap has been delivered from the plodder, a feed bar, means for actuating the feed bar, the operation of which is controlled by the trip mechanism, 115 and a knife cooperating with the feed bar to sever the predetermined length of soap.

12. A soap cutting machine having in combination with a plodder which delivers the soap in a continuous stream, a plunger reciprocating at a regular speed on a plane below the plane of the travel of the soap stream, cutting devices through which the plunger is adapted to force a bar of soap cut from the soap stream, a housing in which the plunger is retracted at the end of its rearward movement, the soap stream being delivered along the upper surface of the forward end of the housing, a knife, a feed bar arranged to reciprocate on the housing, means for 120 125 130

actuating the feed bar, a trip mechanism for determining when a predetermined length of soap has been delivered from the plodder and functioning when actuated by the soap stream to release the means for actuating the feed bar to cause the latter to push the soap stream off the housing and at the same time against the knife to sever the soap stream.

10 13. A soap cutting machine having in combination with a plodder which delivers the soap in a continuous stream, a plunger reciprocating at a regular speed on a plane below the plane of the soap stream, cutting devices between which the plunger is adapted to force a bar of soap cut from the soap stream, means for actuating the plunger, there being lost motion between the plunger and its actuating means permitting the plunger to momentarily remain stationary at the end of its forward and rearward movements, a knife mounted beside the path of travel of the soap stream and arranged to move with the soap stream when engaged thereby, a feed bar located on the plane of the soap stream, means for reciprocating the feed bar, a trip mechanism arranged to determine the length of soap to be cut from the soap stream and functioning to control the operation of the means for reciprocating the feed bar, yieldingly mounted pins projecting rearwardly from the plunger, and fingers secured to the feed bar and adapted to engage the pins on the plunger when the pins are in the path of travel of the fingers on the forward movement of the feed bar.

14. A soap cutting machine having in combination with a plodder which delivers the soap in a continuous stream, a plunger reciprocating at a regular speed on a plane below the plane of the soap stream, cutting devices through which the plunger is adapted to force a bar of soap cut from the soap stream, means for actuating the plunger, there being lost motion between the plunger and its actuating means permitting the plunger to momentarily remain stationary at the limit of its forward and rearward movements, a feed bar arranged to reciprocate on the plane of the soap stream, means for actuating the feed bar, a knife movable in the direction of travel of the soap stream, a feed bar adapted to force the soap stream against the knife to sever it, a trip mechanism for determining the length of soap to be severed, said trip mechanism functioning to control the operation of the means for actuating the feed bar, and yielding separable connections between the feed bar and the plunger effective when the feed bar is completing its forward movement and the plunger has begun or is about to begin its forward movement.

15. A soap cutting machine having in

combination with a plodder for delivering the soap as a continuous stream, a plunger reciprocating at a regular speed on a plane below the plane of the soap stream, cutting devices through which the plunger is adapted to force a bar of soap cut from the soap stream, a knife movable in the direction of the travel of the soap stream, a feed bar adapted to push the soap stream against the knife and the severed bar to a position to fall in front of the plunger, means for actuating the feed bar, and a trip mechanism for controlling the actuation of the feed bar comprising a part located in the path of travel in the soap stream, a clutch arranged to be released to drive the feed bar actuating means, a lever for engaging the clutch, a rod for operating the lever, a dog mounted on the rod, a latch for engaging and moving the dog when the part in the path of travel of the soap stream is moved, means for disengaging the dog from the latch to permit it to return it to normal position, and means for actuating the lever to prevent the clutch from making more than one revolution at a time.

16. A soap cutting machine having in combination with a plodder which delivers the soap in a continuous stream, a plunger reciprocating at a regular speed on a plane below the plane of the soap stream, cutting devices through which the plunger is adapted to force a bar of soap cut from the soap stream, a knife mounted to move in the direction of travel of the soap stream, a feed bar adapted to push the soap stream against the knife and the severed bar into position to fall in front of the plunger, means connected with the feed bar for returning the soap stream to its normal path of travel, means for actuating the feed bar, and a trip mechanism adapted to be actuated by the soap stream when a predetermined length of soap has been delivered from the plodder for controlling the operation of the feed bar.

17. A soap cutting machine having in combination with a plodder which delivers the soap in a continuous stream, a plunger reciprocating on a plane below the plane of the soap stream, cutting devices through which the plunger is adapted to force a bar of soap cut from the soap stream, a knife located beside the path of travel of the soap stream and adapted to move therewith when engaged thereby, a knife bar on which the knife is mounted, a guide mounted to move on the knife bar and through which the soap stream passes, a feed bar adapted to push the guide toward the knife to sever the soap stream, means connected with the feed bar for returning the guide and soap stream to normal position, means for actuating the feed bar, and a trip mechanism actuated by the soap stream for controlling the operation of the means for actuating the feed bar.

18. A machine of the character described having in combination with means for delivering an article in a continuous stream at an irregular speed, a plunger reciprocating at a regular speed and adapted to deliver an article placed in front of it to a predetermined point, means for feeding the article from the continuous stream to a position in

front of the plunger, means for actuating the feeding means, and a trip mechanism controlled by the article as it travels in the continuous stream for controlling the operation of the means for actuating the feeding means. 10
